(57) **CLAIM**

The ornamental design for a mathematical educational set, as shown and described.

DESCRIPTION

FIG. 1 is a front planform view of a first embodiment of the mathematical educational set of the present invention.

FIG. 2 is a front planform view of a second embodiment of the mathematical educational set of the present invention.

FIG. 3 is a front planform view of a third embodiment of the mathematical educational set of the present invention.

FIG. 4 is a front planform view of a fourth embodiment of the mathematical educational set of the present invention.

FIG. 5 is a front planform view of a fifth embodiment of the mathematical educational set of the present invention.

FIG. 6 is a front planform view of a sixth embodiment of the mathematical educational set of the present invention.

FIG. 7 is a front planform view of a seventh embodiment of the mathematical educational set of the present invention.

FIG. 8 is a front planform view of an eighth embodiment of the mathematical educational set of the present invention.

FIG. 9 is a front planform view of a ninth embodiment of the mathematical educational set of the present invention.

FIG. 10 is a front planform view of a tenth embodiment of the mathematical educational set of the present invention.

FIG. 11 is a front planform view of an eleventh embodiment of the mathematical educational set of the present invention.

FIG. 12 is a front planform view of a twelfth embodiment of the mathematical educational set of the present invention.

FIG. 13 is a front planform view of a thirteenth embodiment of the mathematical educational set of the present invention.

FIG. 14 is a front planform view of a fourteenth embodiment of the mathematical educational set of the present invention.

FIG. 15 is a front planform view of a fifteenth embodiment of the mathematical educational set of the present invention.

FIG. 16 is a front planform view of a sixteenth embodiment of the mathematical educational set of the present invention.

FIG. 17 is a front planform view of a seventeenth embodiment of the mathematical educational set of the present invention.

FIG. 18 is a front planform view of an eighteenth embodiment of the mathematical educational set of the present invention.

FIG. 19 is a front planform view of a nineteenth embodiment of the mathematical educational set of the present invention.

FIG. 20 is a front planform view of a twentieth embodiment of the mathematical educational set of the present invention.

FIG. 21 is a front planform view of a twenty-first embodiment of the mathematical educational set of the present invention.

FIG. 22 is a front planform view of a twenty-second embodiment of the mathematical educational set of the present invention; and,

FIG. 23 is a front planform view of a twenty-third embodiment of the mathematical educational set of the present invention.

The drawing is lined for color.
